UNITED STATES PATENT OFFICE.

SIDNEY BOWLING HOUSE, OF SATICOY, CALIFORNIA.

STEAM-ENGINE.

SPECIFICATION forming part of Letters Patent No. 737,239, dated August 25, 1903.

Application filed November 29, 1902. Serial No. 133,252. (No model.)

To all whom it may concern:

Be it known that I, SIDNEY BOWLING HOUSE, a citizen of the United States, residing at Saticoy, in the county of Ventura and State of California, have invented a new and useful Steam-Engine, of which the following is a specification.

The invention relates to certain improvements in rotary engines of that general class in which a laterally-movable cylinder-abutment is alternately moved into and out of the path of travel of a revolute piston-wing.

One object of the invention is to provide an improved form of cylinder and cylinder-packing for contact with the revolute web of the piston in order to prevent the escape of steam from the steam-space of the cylinder; and a further object is to provide an improved form of movable cylinder-abutment 20 and abutment guiding and packing devices.

A still further object of the invention is to provide in an engine of this class for the admission of steam to a point in advance of the piston in order to equalize the steam-pressure 25 on opposite sides of the abutment before the latter is withdrawn from the cylinder, and thus reduce friction and lessen the power required for reciprocating the abutment.

A still further object of the invention is to 30 provide an improved mechanism for properly actuating the abutment, the operating mechanism serving to effect a quick reciprocating movement of the abutment during the movement of the piston in either direction.

A still further object of the invention is to 35 provide an improved form of valve-operating mechanism which may be adjusted either by hand or by any suitable form of governor mechanism to regulate the point of cut-off of the actuating fluid and which may be readily reversed to permit the operation of the piston in either direction.

With these and other objects in view the invention consists in the novel construction 45 and arrangement of parts hereinafter described, illustrated in the accompanying drawings, and particularly pointed out in the appended claims, it being understood that various changes in the form, proportions, size, 50 and minor details of the structure may be made without departing from the spirit or

sacrificing any of the advantages of the invention.

In the accompanying drawings, Figure 1 is a longitudinal sectional elevation of a rotary 55 engine constructed in accordance with my invention. Fig. 2 is a plan view of the same. Fig. 3 is a transverse sectional elevation on the line 3 3 of Fig. 2, illustrating the construction of the cylinder and piston. Fig. 4 60 is a similar view on the line 4 4 of Fig. 2. Fig. 5 is a transverse sectional elevation of a portion of the cylinder, drawn to an enlarged scale. Fig. 6 is a detail perspective view of one of the abutment packing-rings. Fig. 7 65 is a similar view of one of the piston packing-rings. Fig. 8 is a detail perspective view of the reciprocating abutment. Fig. 9 is a detail sectional view of a portion of the cylinder, illustrating the by-passes for admitting steam between the piston and abutment prior to the withdrawal of the latter from the cylinder. Fig. 10 is a transverse sectional elevation of a portion of the cylinder of the engine on the line 10 10 of Fig. 5. 75

Similar numerals of reference are employed to indicate corresponding parts throughout the several figures of the drawings.

10 indicates a suitable bed-plate from which rise standards 11, having journal-bearings for 80 the support of a shaft 12, provided at one end with a balance-wheel 13 of any ordinary character. To the bed-plate is secured the engine-cylinder 14, formed of four sections having bolting-flanges and secured together to 85 form a continuous annular steam-space 15 for the reception of the piston wing or blade.

The piston-body 15', which is secured to the shaft 12, is in the form of a wheel or disk having a central webbed portion, which may 90 be either solid or spoked, and a continuous rim 16, the opposite sides of which are finished for contact with annular packing-strips carried by the inner walls of the cylinder. The piston packing-strips are of the character best shown in Figs. 5 and 7, comprising split rings 17, having overlapping ends and normally pressed against the opposite sides of the rim 16 by small compression-springs 18. Turning movement of the rings with the 100 piston is prevented by providing each ring with a projecting tongue 19, adapted to a re-

cess in the wall of the cylinder. The piston 15 carries a piston wing or blade 20, shaped to conform to the contour of the steam-space of the cylinder and provided with an annular 5 packing-ring 21, the wing being counterbalanced, as at 21'. In order to provide for the accurate adjustment of the piston with respect to the cylinder, the sides of the cylinder are provided with recesses 22 for the reception 10 of journal-boxes 23, which are held in place by set-screws 24, passing through suitable flanges formed on the cylinder and adjustable in order to move the shaft to a central position and to lock the boxes in adjusted 15 position, while longitudinal movement of the shafts is prevented by suitable collars 25, secured to the shaft and bearing against the outer faces of the journal-boxes.

At the top of the cylinder and formed integral therewith is an abutment-casing 27, having a removable cap 28 to permit inspection of the abutment and packing, and within said casing are abutment-guides formed by inwardly-projecting ribs 29 at the upper 25 and lower portions of the opposite sides of said casing, the faces of the ribs being finished for contact with the sides of the abutment, and the ribs are continued around the adjacent walls of the steam-space in order to afford steam-tight joints between the abutment-chamber and the steam-space. The abutment is of the character best shown in Fig. 8 and is in the form of a slightly-rounded plate having upper and lower horizontal walls, 30 the lower wall 31 being slightly concave to conform to the contour of the piston on which it rests during the working stroke of the engine. In the top of the abutment 30 is a recess 32 for the reception of the webbed portion 35 of a packing-strip 33, a spring 34 being introduced between the bottom of the recess and the web in order to press the lower concaved wall of the abutment against the periphery of the piston-body. The forward 40 edge of the abutment is slightly rounded or tapered to facilitate the entrance of the abutment between a pair of annular packing-strips which surround the walls of the steam-space of the cylinder at the juncture of the latter 45 with the abutment-chamber. The packing-rings 35 are seated in annular recesses formed in the ribbed portion of the abutment-casing, and each ring is provided with a plurality of lugs 36, perforated for the passage of bolts 50 37, the lugs being seated in recesses of a depth less than that of the recesses which receive the packing-rings in order that the inner portions of said rings may be held steam-tight in the recesses. The rings are projected by 55 means of springs 39, encircling the bolts and bearing against the inner faces of the lugs, the extent of outward movement being regulated by the bolts 37.

On the shaft 12 is secured a wheel 40, having a peripheral cam-groove 41 for the reception 60 of a roller 42, carried by a pin 43, depending from a rocker-arm 44, the opposite

end of the rocker-arm being mounted on a stud 45, carried by the frame. The pin 43 is also connected by a rod 46 to a cross-head 70 47, adapted to guides 48, carried by the frame, and the cross-head is connected to the abutment by a rod 49, extending through a stuffing-box 50 at one end of the abutment-chamber. It will be noticed on reference to Fig. 2 75 that the cam-groove 41 has an abrupt actuating-surface for effecting a quick reciprocating movement of the abutment, so that the steam may be allowed to act expansively on the piston-wing until the latter has nearly 80 completed a full revolution. In order to hold the roller 42 in proper position, the rocker-arm 44 is preferably provided with a projecting tongue 51, under the control of a guiding-bar 52, carried by the frame of the engine. 85

Steam or other actuating fluid is admitted to the cylinder through a pipe 55, having a suitable controlling-valve 56, and the steam-pipe is coupled to two branch pipes 57, leading into the cylinder at points on opposite 90 sides of the abutment, a three-way cock 58 being introduced at the juncture of the several pipes in order to direct the steam through one or other of the branch pipes in accordance with the direction of travel of the piston. 95

At a point on the cylinder opposite the two steam-inlet ports are two exhaust-ports 60, leading through valve-casings 61, in which are spring-closed valves 62, and on the outer face of the cylinder are pivot-pins 63 for the support of levers 64, the upper ends of which are adapted to engage the valve-stems, the levers being connected by a link 65 to an operating-lever 66 and being moved simultaneously to open one or other of the valves in accordance with the direction of travel of the piston. The valve-operating lever is provided with a latch-bar and locking-bolt adapted to engage a notched locking-segment 67 of the usual construction. 110

In lieu of the usual slide-valve a throttle-valve 69 is placed in a valve-casing 70, connected in the steam-supply pipe 55, said valve being acted upon by an adjustable operating mechanism for altering the point of cut-off in accordance with the speed and load of the engine, the mechanism being capable of adjustment to reverse position when the engine is to 115 revolve in the opposite direction.

Mounted loosely on the shaft 12 are two 120 cam-disks 72 and 73, having elongated hubs 74 and 75, respectively, the ends of the hubs bearing against stationary collars 76, secured to the shaft and serving to prevent longitudinal movement of the hubs and disks without interfering with the rotating movement thereof. The disks 72 and 73 are provided with peripheral grooves for the reception of an antifriction-roller 77, depending from one arm of a bell-crank lever 78, pivoted on a pin 125 79, carried by a suitable supporting-bracket, the opposite arm of said bell-crank lever being connected by a link 80 to the stem of the throttle-valve. The actuating portion of the 130

cam-disk 72 is in the form of a shoulder 81, which by engagement with the antifriction-roller 77 moves the valve to opened position after the piston-wing has traveled for the full 5 distance beyond the movable abutment. The valve remains in this position until the anti-friction-roller is engaged by one or other of the shoulders 82 82, carried by the cam-disk 73, and is then moved to closed position. The 10 interval between the opening and the closing movement of the valve is governed by circumferential adjustment of the cam-disk 73, while the cam-disk 72 is adjustable only to one or other of two positions in accordance with the 15 direction of travel of the piston.

The hub 74 of cam-disk 72 is provided with a pair of radially-disposed pins 84, projecting through helical grooves 85 in a sleeve 86, keyed to the shaft and free for longitudinal 20 movement thereon. The shaft is provided with an annular groove for the reception of a ring 87, connected by pins to the bifurcated end of an arm 88, carried by a rock-shaft 89, located near the bed-plate of the machine. 25 At the other end of the rock-shaft, near one side of the bed-plate, is an adjusting-lever 90, having a latch-bar 91 and bolt for engaging a notched locking-segment 92, carried by the bed-plate. The movement of the operating- 30 lever causes a corresponding longitudinal movement of the sleeve 86, and the helical grooves 85 of said sleeve cause, through the pins 84, a partial revolution of the hub 74 and cam-disk 72, the operating-shoulder 81 of the 35 latter being properly adjusted with respect to the abutment, so that the shoulder may properly act on the valve-lever in either direction of movement.

The hub 75 of the disk 73 is provided with 40 pins 93, projecting through helical slots 95 in a longitudinally-movable sleeve 96, held to the shaft by suitable feathers or keys 97. This sleeve is provided with an annular groove for the reception of a ring 98, carried 45 by the bifurcated end of a lever 99 on a rock-shaft 100, and at the outer end of said rock-shaft is an adjusting-lever 101, having a latch-lever and locking-bolt for engagement with a notched segment 102. The adjustment in 50 this case may be to an extent equal to a complete revolution of cam-disk 73, so that the relative positions of the valve-actuating shoulders may be reversed or the distance between the valve-opening and the valve-closing shoulders adjusted to alter the amount 55 of steam admitted to the engine. In some cases the adjustment of the cut-off may be governed by an ordinary form of centrifugal governor in order to render the engine automatic and properly regulate the speed.

The cylinder is provided with valved pipes 105, arranged near the abutment and constituting by-passes to permit the passage of steam around the piston to a point between the 60 forward face of the piston and the abutment, and thus automatically equalize the pressure on opposite sides of the abutment prior to

the opening movement thereof, thus reducing the friction and lessening the amount of power required for reciprocating the abutment. 70

If desired, the three-way cock, the exhaust-valves, and by-pass valves may be connected to a single system of levers and all operated at a single movement in reversing.

Having thus described the invention, what 75 I claim is—

1. The combination in a rotary engine, of the cylinder having an annular steam-space, a piston disposed within the cylinder, a piston-wing carried by the piston and fitting within the steam-space, split packing-rings carried by the opposite walls of the cylinder and bearing against the sides of the piston, and laterally-projecting tongues forming a part of said rings and fitting within recesses 85 in the walls of the cylinder.

2. The combination in a rotary engine, of the cylinder having an annular steam-space, a piston, a piston-wing carried thereby and fitting within the steam-space, an abutment 90 movable into and out of the path of the piston-wing, an abutment-casing, and curved packing-strips carried by the walls of the casing at points around the circular wall of the steam-space and adapted for contact with 95 the opposite sides of said abutment.

3. The combination in a rotary engine, of the cylinder having an annular steam-space, a piston, a piston-wing fitting within the steam-space, an abutment containing and 100 guiding casing, an abutment mounted within the casing and movable into and out of the path of movement of the piston-wing, packing-strips arranged within curved recesses in the opposite sides of the casing at points 105 around the circular wall of the steam-space, and springs for forcing said packing-strips into contact with the movable abutment.

4. The combination in a rotary engine, of the cylinder having an annular steam-space, 110 a piston, a piston-wing fitting within the steam-space, an abutment-guiding casing, packing-strips arranged within curved recesses in the opposite sides of the casing at points around the circular wall of the steam-space 115 for contact with the abutment, and an abutment movable in a plane parallel with the axis of rotation of the piston and having its opposite sides tapered or inclined to pass between the packing-strips. 120

5. The combination in a rotary engine, of the cylinder having an annular steam-space, a piston, a piston-wing arranged within the steam-space, an abutment-casing, a movable abutment mounted within the casing and 125 movable into and out of the path of travel of the piston, said abutment having a curved lower edge conforming to the contour of the steam-space, and a spring-pressed bar at the upper edge of said abutment for contact with 130 the upper wall of the casing.

6. The combination in a rotary engine, of the cylinder having an annular steam-space, a piston, a piston-wing disposed within the

- steam-space, an abutment-casing having curved recesses in its opposite sides at points around the steam-space, curved packing-strips adapted to the recesses, lugs projecting from 5 the packing-strips and extending into recesses formed in the walls of the casing, springs bearing against the lugs, bolts for limiting the outward movement of the lugs and strips, and an abutment adapted to move between the packing-strips.
7. The combination in a rotary engine, of the cylinder having an annular steam-space, a piston, a piston-wing disposed within the steam-space, an abutment-guiding chamber, 15 an abutment mounted therein and movable into and out of the path of travel of the piston-wing, a shaft carrying the piston, a cam-wheel mounted on the shaft and provided with a peripheral cam-groove, a pivoted arm, 20 a roller mounted near one end of the arm and extending into the cam-groove, means connecting the arm to the abutment, and an auxiliary guiding-bar adapted to engage the outer end of said arm.
8. The combination in a rotary engine, of the cylinder having an annular steam-space, a piston, a piston-wing disposed within the steam-space, a movable abutment, and a bypass connecting adjacent portions of the cylinder near the abutment to permit the passage of steam around the piston as the latter approaches said abutment.
9. The combination in a rotary engine, of the cylinder having an annular steam-space, 35 a piston, a piston-wing disposed within the steam-space, an abutment movable into and out of the path of travel of the piston-wing, and valved by-passes connecting spaced portions of the cylinder on opposite sides of the 40 abutment to permit the passage of steam around the piston-wing, as the latter approaches the abutment from either direction.
10. The combination in a rotary engine, of the cylinder, a piston therein, a steam-inlet 45 valve, a circumferentially-adjustable valve-operating cam comprising a pair of cam members having edge flanges to form a grooved cam, and means for independently adjusting said members.

11. The combination in a rotary engine, of 50 the cylinder, a piston therein, a shaft, a valve-operating cam comprising a pair of independently-adjustable members, each member having a continuous annular flange forming a continuation of its cam-surface to limit the 55 movement of the valve-operating mechanism and a steam-inlet valve operable by said cam.

12. The combination in a rotary engine, of 60 the cylinder, a piston disposed in said cylinder, a shaft, a pair of independently-adjustable cams carried thereby and flanged to form a continuous cam-groove, a hub or sleeve forming a part of each cam, pins carried by said hub, a longitudinally-adjustable sleeve feathered to the shaft and provided with inclined slots for the reception of the pins, 65 means for adjusting said sleeves, and a steam-inlet valve controlled by the cams.

13. The combination in a rotary engine, of 70 the cylinder, a piston therein, a steam-inlet valve, a shaft, a pair of cam-disks each having an independent hub and mounted on the shaft, means for operatively connecting the cams to the valve, pins projecting from the hubs of the cams, sleeves feathered to the 75 shaft and extending over the hubs, each of said sleeves being provided with a helical slot for the reception of the pins, and adjusting-levers operatively connected to said sleeves.

14. The combination in a rotary engine, of 80 the cylinder, a movable abutment carried by the cylinder, a piston, cylinder escape-ports arranged in the walls of the cylinder at opposite sides of the abutment, spring-closed 85 valves in the escape-ports, a valve-adjusting lever, a pair of valve-operating levers connected to each other and to the adjusting-lever, and means for locking the levers in adjusted position in order to maintain either valve in open position. 90

In testimony that I claim the foregoing as my own I have hereto affixed my signature in the presence of two witnesses.
